DESIGN FOR A FABRIC TESTING DISPLAY STAND

Herbert W. Wilkinson, Jr., Southbridge, Mass.

Application September 6, 1945, Serial No. 121,895

Term of patent 14 years

(Cl. D80—9)

To all whom it may concern:

Be it known that I, Herbert W. Wilkinson, Jr., a citizen of the United States of America, residing at Southbridge, in the county of Worcester and State of Massachusetts, have invented a new, original, and ornamental Design for a Fabric Testing Display Stand, of which the following is a specification, reference being made to the accompanying drawing, forming a part thereof.

Fig. 1 is a front elevational view of a fabric testing display stand showing my new design;

Fig. 2 is a side elevational view of the fabric testing display stand shown in Fig. 1.

The characteristic features of my design are shown in full lines in the drawing.

I claim:

The ornamental design of a fabric testing display stand, substantially as shown and described.

HERBERT W. WILKINSON, JR.
